(57) CLAIM

The ornamental design for a mobile dental vehicle interior, as shown and described.

DESCRIPTION

FIG. 1 is a perspective view of a mobile dental vehicle interior showing my new design;

FIG. 2 is a view illustrating the patient seating and rear area as viewed from the forward area thereof;

FIG. 3 is a view illustrating the forward area as viewed from the patient chair area thereof;

FIG. 4 is a first side elevation view thereof;

FIG. 5 is a second side elevation view thereof;

FIG. 6 is a top elevation plan view as viewed from above the patient chair area thereof; and,

FIG. 7 is a view illustrating the ceiling area as viewed from the patient chair area.

The broken lines illustrate portions of the mobile dental vehicle interior that do not form a part of the claimed design. The slash lines indicate boundaries and form no part of the claimed design.
